UNITED STATES PATENT OFFICE.

JOHN F. TOOMEY, OF NEW YORK, N. Y., ASSIGNOR TO AMERICAN TELEPHONE AND TELEGRAPH COMPANY, A CORPORATION OF NEW YORK.

MONITORING AND CONTROLLING CIRCUITS FOR PROGRAM DISTRIBUTION.

Application filed July 31, 1924. Serial No. 729,376.

This invention relates to transmission systems, and more particularly to monitoring and controlling arrangements for such systems.

- 5 In a system for the transmission of programs over wires, it is proposed to extend trunks from the main studio to central offices or distributing points. At each central office the trunk may be equipped with one or more 10 amplifiers, as may be required, and from the output terminals of these amplifiers a number of branch trunks will radiate to local distributing points, such as apartment houses, at which local points other amplifiers may be 15 provided. The output terminals of these amplifiers may in turn be connected to a plurality of branches extending to local subscribers provided with loud speakers or head 20 receivers.
- 20 In a system of the type above described, it is essential that the attendant at the main studio have some means of knowing that the operation of the various parts of the system, as well as the system as a whole, is satisfactory. It is, therefore, one of the purposes of 25 the present invention to provide monitoring and control circuits to enable the studio attendant to easily and quickly determine whether or not the system is operating in a satisfactory manner. In the preferred arrangement, the monitoring and control circuit is operated over a separate pair of wires which parallel the trunk carrying the program to the central office and which is extended 30 as a common circuit to each apartment house equipment.
- 35 Among other advantages, the arrangements of the present invention permit the studio attendant to monitor on the output of any amplifier, that is, either the main amplifier at the central office or the individual amplifiers at the different apartment houses or at other central offices. The studio attendant is also enabled to adjust the output of the main 40 amplifier at the central office. Furthermore, the studio attendant may call the central office attendant on the telephone when required, and the central office attendant may likewise 45 call the studio directly if desired.
- 50 In accordance with the present invention it is also proposed to provide visual or audible signals at the studio which indicate that the system is functioning properly, that is, when all the amplifier and power equipment 55 at the central office and apartment houses is in an operative condition. In case any of this equipment fails, the signaling system indicates this fact. It is preferred to transmit all of the signals over the control circuit between the studio and central office, leaving the program trunk free of all other apparatus other than that required for transmitting the program. Between the central office and the apartment houses, however, the signals may be sent over the trunk carrying the program.
- 60 The invention may now be more fully understood from the following description when read in connection with the accompanying drawing, Figures 1, 2 and 3 of which, when placed end to end, illustrate the preferred embodiment of the invention.
- 65 Referring to the drawing, PT designates a main trunk extending from the studio at the main station to a central office provided with amplifying equipment, as indicated at A and A' in Fig. 2. Bus-bars 10 are connected to the output side of the amplifiers A and A' and to these bus-bars a plurality of trunks, such as PT₁, are connected, each trunk leading to an outlying apartment house or other local 70 distributing point. At each apartment house, amplifying equipment, as indicated at A₁ and A'₁ in Fig. 3 is provided. Bus-bars 11 are connected to the output side of the amplifier at the apartment house and distributing 75 circuits leading to each subscriber's station may be connected to such bus-bars.
- 80 In order that the studio attendant may monitor on the various trunks to determine the quality and volume of transmission being received at various points, a monitoring circuit MC is provided, as shown in Fig. 1, which may be plugged by means of a plug P into jack J of a monitoring trunk MT, extending from the studio to the central office, at 85 which point the trunk may be switched under the control of the attendant at the studio either to the output bus-bars of the amplifier A' at the central office, over the conductors 12, or to an auxiliary monitoring trunk MT' having branches which may be connected to the output bus-bars of the amplifier at any 90 apartment house, the connection of these branches being controlled from the studio.
- 95 In order to control the switching of the monitoring trunks to the output bus-bars of the various amplifiers, the studio attendant is provided with a dial 13 by means of which impulses may be transmitted to operate step-by-step switches SW and SW'. The switch 100
- 105
- 110

SW controls the establishment of connections from the monitoring trunk to the output bus-bars of any amplifier either at a central office or at an apartment house. The switch 5 SW' may selectively operate to adjust the potentiometer PO, associated with the input side of the amplifier A at the central office in Fig. 2.

At the central office a spare amplifier SA 10 may be provided so that if the amplifying equipment A—A' is not functioning properly the spare amplifier may be substituted therefor under the control of the switch SW'.

A telephone set 14 is provided for the use 15 of an attendant at the central office and by sending a proper code by means of the dial 13 the studio attendant may actuate the switch SW to connect the central office attendant's set to the trunk MT, thereby enabling the two attendants to converse with each other.

Further details of the apparatus will be clear from a description of the operation thereof, which is as follows: When the attendant at the studio desires to start the 25 program, the program trunk PT is connected to the studio transmitting apparatus by means of the Jack PJ, and the key K associated with the monitoring trunk MT is actuated. A circuit is closed by the key K from 30 battery V_1 through marginal relay S_1 , over the inner right-hand normal contact of the relay S, contact of the key K, midpoint of retardation coil RC, thence over the two sides 35 of the trunk MT, midpoint of the retardation coil RC' and thence through the winding of the marginal relay PM and the high resistance winding of the relay S_2 to ground. Relay S_1 is marginal and does not receive sufficient 40 current in series with the high resistance winding of the relay S_2 to operate. Relay PM is also marginal and only operates in series with the high voltage battery V_2 , as will be described later. The relay S_2 is energized, however, and completes a circuit 45 from ground, over its front contact, through the winding of the relay S_3 and through the winding of the relay S_4 to battery. Relay S_3 , upon being energized, performs no useful 50 function at this time but relay S_4 completes a circuit from ground, over its front contact, over conductor 14 and over conductor 15, through the winding of relay V to battery V_1 .

55 At its left-hand front contact, relay V establishes a circuit for the filaments of the amplifiers A and A' from battery V_1 , over the left-hand front contact of relay V, through resistance 15 and through the filaments of the tubes 16, 17 and 18 in series to ground. As soon as the filaments of the tubes glow, plate current from the 60 350 volt source is supplied through the choke coil 19, through the winding of relay Y to the plates of the tubes 16 and 17 and

from the choke coil 19 through the resistance 20 and the winding of the relay I to the plate of the tube 18. If the 350 volt source is a normally operative source, the space current at once begins to flow through the relays 70 I and Y. If, however, the 350 volt source is a generator, the outer right-hand front contact of the relay V may be arranged to start the generator in a manner well known in the art, so that as soon as the generator 75 gets up speed and generates the desired voltage, the current will flow through the relays I and Y to energize their windings. As soon as these relays are energized, a circuit is completed from battery, through the right-hand 80 winding of the relay S_{12} , over the front contact of relay Y, and over the front contact of relay I, and thence over the conductor 14 to ground, over the front contact of relay S_3 . Relay S_{12} , upon being energized, connects 85 the low resistance winding of relay S_2 (see Fig. 1) over conductor 21, over the back contact of relay S_{13} , over the front contact of relay S_{12} and over conductor 22 to a contact 90 controlled by the relay C in Fig. 3. This circuit will be completed upon the energization of the relay C in a manner to be described later.

Returning to the relay V, battery V_1 is connected over its inner right-hand front contact to the auxiliary bus-bar 23', associated with the trunk bus-bars 10, so that current flows over the conductor 24', over the back contact of relay C_1 , through the winding of marginal relay C_1 to the midpoint of the retard coil RC_2 , over the two sides of the trunk PT₁ to the midpoint of the retard coil RC_3 and thence through the high resistance winding of the relay C_2 and through the winding of the marginal relay C_3 to ground. Relay 100 C_1 is marginal and does not receive sufficient current in series with the high resistance winding of relay C_2 to be energized. Relay C_3 is also marginal and only operates when its circuit is connected to the high voltage 105 source V_2 , as will be described later. Relay C_2 is energized, however, and completes a circuit from ground, over its front contact, through the winding of relay C_4 to battery. Relay C_4 , at its right-hand front contact, connects battery through the resistance 23, choke coil 24, through the filaments of tubes 25, 26 and 27 in series to ground. As in the case 110 of the amplifying equipment at the central office in Fig. 2, the 350 volt plate source may be a dynamo machine, in which case the left-hand contact of the relay C_4 may close a circuit to start the dynamo machine in a well known manner. As soon as the space current 115 flows through the tubes, the relays I and L will be energized to complete a circuit from ground, over the front contact of the relay L, front contact of relay I, through the left-hand winding of the relay H to battery. Relay H is then locked up over its right-hand 120 125 130

front contact and over the front contact of relay C_2 to ground.

At its outer left-hand front contact relay H completes a shunt path through the low resistance winding of relay C_2 over the outer left-hand front contact of the relay H_8 , back contact of relay C_5 , to the terminal of the winding C_3 , this shunt path being in shunt with the high resistance winding of the relay C_2 . The current is increased through the winding of the relay C_8 but is still insufficient to energize said winding. The increase in the current flow over the circuit is sufficient, however, to operate the marginal relay C_1 , which completes a circuit from ground, over its front contact and over the similar contacts of other relays corresponding to C_1 and associated with other trunks, and thence through the winding of the relay C to battery. It will be understood that the contacts of the relays corresponding to C_1 of other trunks associated with the bus-bars 10 will be energized in a manner similar to that described in connection with the circuits associated with the trunk PT_1 .

Upon the relay C attracting its armature, ground is connected to the conductor 22, thereby establishing a path through the low resistance shunt winding of relay S_2 (see Fig. 1) from ground, over the front contact of the relay C , over conductor 22, over the front right-hand contact of relay S_{12} , right-hand back contact of relay S_{13} , over conductor S_{21} , and through the low resistance winding of the relay S_2 in parallel with its high resistance winding to the terminal of the marginal relay PM . The current is increased through the marginal relay PM but is insufficient to actuate said relay. The increase in the flow of current over the circuit including the relays PM and S_1 , however, is sufficient to energize the marginal relay S_1 , which attracts its armature and closes the circuit from ground, over its front contact and through the winding of the relay X . The relay X , at its right-hand front contact, completes a circuit from ground, over the back contact of relay Y , over the front contact of relay X and through the O. K. signal lamp 28. The glowing of the O. K. lamp indicates that all of the apparatus is in normal operative condition so that the program may proceed.

If the filament of either tube 16 or tube 17 at the central office should burn out, the decrease or interruption, as the case may be, of the space current through the relay Y will cause said relay to be deenergized and a circuit will then be completed from ground, over the front contact of the relay S_3 (see Fig. 1), over conductor 14, over the front contact of relay I , back contact of relay Y , through the left-hand locking contact and locking winding of the relay S_{12} , through the winding of the relay S_{13} to battery. The

relay S_{13} , upon being deenergized, at its left-hand contact closes the circuit of the bell 34 to notify the attendant at the central office. At its right-hand contact relay S_{13} opens the shunt circuit through the low resistance winding of the relay S_2 previously traced over conductor 21. This causes the marginal relay S_1 to be deenergized, thereby completing a circuit from battery, through the winding of the relay X and over its left-hand locking contact, over the contact of the restored key 30, and through the winding of relay Y to ground. Relay Y is now locked up in series with the relay X and at its inner right-hand contact opens the circuit of the O. K. signal 70 28, and at its outer right-hand front contact completes a circuit through the alarm signal 31 and the relay 32. The relay 32 closes a circuit of the bell 33 so that an audible as well as a visual signal is given at the studio. 75

If the filament of the tube 18 at the central office should burn out the relay I would be released. If the 350 volt power source should fail, both relays I and Y would be released. 80 In either case a circuit would be completed from ground to conductor 14, over the back contact of relay I , over the left-hand locking contact and locking winding of relay S_{12} , through the winding of relay S_{13} to battery. 85 Relay S_{13} would thus be energized with the same results as previously described. 90

If the filament of the tube 27 at the apartment house should burn out, the space current would be interrupted so that the relay I would release its armature and close a circuit from ground, over the front contact of relay L , back contact of relay I , over the inner left-hand front contact of relay H , and through the winding of relay C_5 to battery, 100 thereby energizing the relay C_5 . If the filament of tubes 25 or 26 should burn out, the space current through the relay L would be interrupted. In case the 350 volt power source should fail, both relays I and L would be released. In either case, a circuit would be completed from ground, over the back contact of relay L , over the inner left-hand front contact of relay H , and through the winding of relay C_5 to battery, energizing the relay C_5 . 105

Relay C_5 , upon being energized, opens the low resistance shunt through the low resistance winding of the relay C_2 , thereby decreasing the current flow through the marginal relay C_1 and causing said relay to release its armature. Relay C_1 opens a circuit of the relay C , which in turn disconnects ground from conductor 2 and thereby opens the low resistance shunt circuit through the low resistance winding of the relay S_2 , thereby causing a decrease in current through the relay S_1 (see Fig. 1), causing said relay S_1 to release and give the alarm signal, as previously described. 110 115 120 125 130

Upon receiving the alarm signal, an attendant may be sent to repair the difficulty in the usual manner. In case the trouble arose in connection with the amplifier at the apartment house, the relay C_5 would be released as soon as the relays I and L are again energized, thereby again closing the low resistance shunt through the low resistance winding of the relay C_2 . This in turn closes the shunt circuit previously traced through the low resistance winding of the relay S_2 (see Fig. 1) and causes the marginal relays S_1 to be again energized. The energization of the relay S_1 at once short circuits the winding of the relay Y, which is released to open the alarm circuit and close the circuit of the O. K. signal 28. In case the trouble arose in connection with the amplifier at the central office, relays I and Y will again be energized as soon as the trouble is repaired, thereby opening the circuit of the relay S_{12} and in turn closing the low resistance shunt through the low resistance winding of the relay S_2 . Relay S_1 is then again energized with the same results, as already stated.

When the studio attendant wishes to discontinue the program, the key K is restored, thereby releasing relay S_2 . Relay S_2 in turn opens the circuit of relay S_3 , which disconnects ground from the relay V associated with the central office amplifier. Relay V, upon releasing, at its left-hand contact opens the filament circuit of the amplifiers A and A', causing relays I and Y to be deenergized and relay S_{12} to be restored to normal. Relay V, at its right-hand contact, disconnects ground from the bus-bar 23', thereby opening the circuit of the relays corresponding to C_1 and C_2 of all the trunks, such as PT₁. Relay C_2 is released, thereby restoring the relays C_4 and H to normal. Relay C_4 disconnects battery from the filament supply circuit of the amplifiers A₁ and A'₁, thus bringing all apparatus to its normal condition.

When the attendant at the studio wishes to monitor on the output of the central office amplifier, he inserts the plug P of the monitoring circuit MC in the jack J of the monitoring trunk MT. The insertion of the plug P closes the circuit of the relay S. The relay S at its inner right-hand front contact disconnects the relay S_1 from the circuit previously traced over the key K (which is closed as previously described in order to render all of the apparatus operative) and connects the circuit over the key K from the inner right-hand front contact of relay S, over the sleeve conductors of the jack J and plug P, through the resistance 35 of the dial 13, over the normal contact of the dial 13, over the contact of the release key 36, to battery V₂. The battery V₂ is a high voltage battery but the resistance 35 is so proportioned as to maintain the same current flowing through the relays PM and S_2 at the central office as that

obtained with the battery B₁. The relay S_2 therefore remains in operative condition.

The attendant at the studio then operates the dial 13 to send a proper number of impulses to operate the switches SW and SW' to the desired point, which in this case we will assume to be the sixth point of the switch. As soon as the dial is operated to the off normal position, the off normal contacts of the dial short circuit the resistance 35, thereby permitting additional current to flow to operate the marginal relay PM as well as the relay S_2 . As the dial returns to normal, impulses are sent over the circuit including the relays PM and S_2 by interrupting the circuit through the impulse contact of the dial. As soon as the relay PM was energized, as originally described, it closes a circuit through the stepping magnet SM and through the slow release relay SR at its front contact. The slow release relay SR holds open the circuit which extends over the back contact of the relay RM to the outer armature of the relay S_6 . The relay SR, being slow releasing, remains energized during the interruptions of its circuit each time the armature of the relay PM falls off in response to the transmission of an open circuit impulse. This prevents ground being connected to the arm of the switch SW or switch SW', as the case may be, during the momentary intervals that the armature of the relay PM is on its back contact.

The impulses transmitted through the stepping magnet SM advance the wipers of the switches SW and SW' to the sixth contacts of each switch. The relay S_6 at its outer armature controls the connection from the back contact of the relay PM to the arms of said switches. When the relay S_6 is deenergized, the arm of the switch SW' is disconnected from the circuit and the arm of the switch SW is made effective. When the relay S_6 is energized, the connections to the switch wipers are reversed, the wiper switch SW being disconnected and the wiper switch SW' being rendered effective. As soon as the dial 13 has reached its normal condition, the short circuit about the resistance 35 is removed so that the current flowing through the relays PM and S_2 is reduced sufficiently to deenergize the relay PM. The slow release relay SR, which prevented the closing of a circuit to the wipers of either switch SW or SW', after a moment releases its armature, thereby completing a circuit from ground, over the back contact of the relay PM, back contact of relay SR, back contact of relay RM, outer right-hand back contact of relay S_6 over the wiper of the switch SW and the sixth contact of the switch SW, through the winding of the relay S_4 to battery. Relay S_4 , upon being energized, disconnects the trunk MT from the trunk MT' and connects the trunk MT over the conductors 12 to the

output bus-bars of the amplifiers A and A'. The studio attendant can now listen to the output circuit of the amplifying equipment at the central station by means of his receiver, which is connected across the monitoring circuit.

Assuming now that the studio attendant wishes to monitor on the output of one of the apartment house amplifiers, he must first restore the switches SW and SW' to normal position, for these switches when once advanced remain in their advanced position until restored by some special action. The restoration of the switches may be accomplished by either momentarily removing the plug P from the jack J or by momentarily operating the release key 36. Momentarily withdrawing the plug causes a momentary interruption of the circuit over the controlling key K for the reason that the relay S is slow to release when the plug is withdrawn and does not immediately connect the circuit over the key K to the winding of the relay S. The momentary opening of the release key 36 will obviously momentarily interrupt the circuit over the key K for the reason that the release key 36 is directly in the circuit. Either of these operations, therefore, causes a momentary release of the relay S₂. Relay S₃, however, being a slow release relay, is not released under these conditions and maintains the ground connection to the conductor 14 so that the amplifying equipment remains in operative condition. Relay S₈ being a quick release relay, opens its contact but performs no useful function at this time.

Relay S₂ is momentarily released, thus momentarily connecting ground over its back contact, over the off normal contact 37 (which was closed as soon as the switches SW and SW' moved off normal), and through the winding of the release magnet RM to battery. The release magnet restores the switches SW and SW' to normal. A contact is provided on the release magnet RM which holds open the circuit to the brushes while the switches are being restored to normal.

In order to monitor on one of the apartment house amplifiers, for example, the amplifiers A₁ and A'₁, the attendant, after restoring the switches to normal, as above described, will then dial the proper code number, which is assumed to be 3, to step the switches SW and SW' around to the third terminal. The third terminal of the switch SW is connected over conductor 38, through the winding of the relay C₇ to battery V₁ (see Fig. 3). The switches SW and SW' are advanced in the manner previously described by the operation of the dial, and the relay S₈ not being energized, a circuit will be completed at the close of the dialing operation from ground, over the back contact of the relay PM, back contact of relays SR and RM, outer back contact of relay S₆, wiper of the

switch SW, third contact of switch SW, over the conductor 38 and through the winding of the relay C₇ to battery. Relay C₇, upon operating, disconnects the circuit through relay C₁ and the retard coils associated with the trunk PT₁, from the battery connection over the conductor 14, and over the inner right-hand front contact of relay V to the battery V₁, and substitutes a direct connection to the high potential battery V₂. Therefore, the current through the circuit of relays C₁, C₂ and C₃ is now sufficiently increased to operate the marginal relay C₈. Relay C₈ closes a circuit of the relay C₆ and connects the monitoring trunk MT' to the bus-bars of the amplifying equipment A₁ and A'₁ at the apartment house shown in Fig. 3. The studio attendant is now enabled to listen on the output circuit of this amplifier.

It should be noted that the monitoring and control circuit MT' is common to all of the apartment house amplifiers that are fed from the amplifying equipment A—A' at the central office, so that by dialing the proper number the attendant at the studio can monitor on the amplifier at the central office or on any apartment house amplifier connected to the central office amplifier.

When the studio attendant is through monitoring on the circuit, the switch at the central office is resorted to normal either by means of the release key 36 or by removing the plug P from the jack J, as already described. Let us assume now that the studio attendant has dialed the proper number to advance the wiper of the switch SW to its sixth contact so that the attendant is monitoring on the output circuit of the central office amplifier equipment A and A', and that the attendant wishes to increase or decrease the volume of the output of the amplifier. In this case, the switches SW and SW' are restored to normal as before and the attendant dials a code number, which will be assumed to be 9. The operation of the dial will therefore advance the wiper of the switch SW to its ninth contact, which is connected to the winding of the relay S₅ (the wiper of the switch SW' is, of course, advanced at the same time but is without effect because the relay S₈ is deenergized). As soon as the dial returns to normal, the ground placed upon the circuit by the back contact of the relay PM completes a circuit of the relay S₅. At its right-hand contact, relay S₅ disconnects ground from the conductor 39, thereby releasing any of the relays S₇ to S₁₀, inclusive, which may have been previously locked up, and at its right-hand front contact relay S₅ completes a circuit through the right-hand winding of the relay S₆. S₆ is locked up through its right-hand winding and over its inner right-hand front contact, and over the front contact of relays S₈ and S₉ to ground. The action of the relay S₆ is only momentary for it com-

- pletes a circuit at its left-hand front contact, over the off normal contact 37, over the release magnet RM of the switches, thereby restoring the switches SW and SW' to normal. 5 The relay S₆, however, remains operated and at its outer right-hand front contact the wiper of the switch SW is disconnected and the wiper of switch SW' is connected to the circuit controlled by the relay PM.
- 10 The dial is now again operated to send a second set of impulses which will step the switches SW and SW' around to the proper contact to close the circuit of one of the potentiometer controlling relays S₈, S₉ or S₁₀.
- 15 Assuming the code number transmitted is 9, the brush of the switch SW' will be advanced to its ninth contact and as soon as the dial is restored to normal, ground is connected over the back contact of the relay PM to the 20 outer armature of the relay S₆ as before, and thence over the outer front contact of said relay S₆, over the wiper of the switch SW', and over conductor 40, through the upper winding of the relay S₁₀ to battery. Relay S₁₀ is 25 energized and locks up through its lower winding and over its lower front contact to grounded conductor 39. The relay S₁₀ upon being energized, connects the input winding of the amplifier A to the outer connections of 30 the potentiometer PO.
- The studio attendant may now operate the release key 36 and restore the switches SW and SW' to normal. The momentary release of the relay S₆ unlocks the relay S₆ so that it is also restored to normal. The attendant may now dial the proper code number to enable him to monitor on the output of the amplifier A' and determine if the setting of the potentiometer is proper.
- 35 It will be apparent that in a similar manner the attendant may, by dialing the proper number of impulses the second time, complete circuits for either of the relays S₈ or S₉ and cause other settings in the potentiometer.
- 40 The first dialing operation in each instance energizes the relay S₆ to unlock any of the relays S₈, S₉ or S₁₀, previously locked up before the final set of impulses is transmitted. It will also be apparent that at any time the 45 attendant may release any of said relays and leave the potentiometer in its normal setting, as indicated in the drawing, merely by dialing nine impulses to operate the relay S₆, which disconnects ground from conductor 39.
- 50 The switches, after being thus advanced, are automatically restored to normal, as previously described, but it will be necessary to operate the release key 36 or momentarily disconnect the plug P from the jack J in order 55 to unlock the relay S₆.
- If the studio attendant should desire to substitute the spare amplifier SA for the amplifying equipment A—A' at the central office, the attendant will first operate the dial 60 to send nine impulses, thereby advancing the
- switch SW to its ninth contact and energizing the relay S₆ to lock up the relay S₆. The switches are automatically restored to normal, as already described, whereupon the attendant dials the second set of impulses to 70 advance the brushes of the switches SW and SW' to their fifth contacts. As soon as the dial is restored to normal, relay PM connects ground over its back contact to the conductor connected to the outer right-hand armature of locked-up relay S₆, so that ground is connected over said armature, over the outer front contact of said relay, over the wiper of the switch SW', fifth contact of switch SW', conductor 41, through the winding of 75 relays S₇ and S₁₁ in series, and thence to battery. Relays S₇ and S₁₁ disconnect the amplifiers A—A' and substitute therefor the spare amplifier SA. Relays S₇ and S₁₁ are locked up over the lowermost front contact 80 of relay S₇ and over conductor 39 to ground, at the back contact of relay S₅.
- 85 After switching the amplifiers as above described, the attendant may restore the switches SW and SW' to normal and release the relay S₆ by momentarily actuating the release key 36 or momentarily withdrawing the plug P, as already described. The relays S₇ and S₁₁ will nevertheless remain energized by reason of the fact that their circuits are 90 locked up. If the operator should thereafter desire to release these relays and again connect the amplifiers A and A' to the circuit, it is only necessary to again dial 9, thereby 95 advancing the switch SW to its ninth contact and closing the circuit of relay S₆, which momentarily removes ground from conductor 39 and unlocks the relays S₇ and S₁₁. The switches are automatically restored to normal by a circuit closed over the left-hand 100 front contact of relay S₅, as previously described, and the relay S₆ may be released by momentarily actuating the release key 36.
- 105 In case the studio attendant wishes to call the central office attendant on the telephone, the plug P of the monitoring circuit MC is inserted in the jack J, as already described, and the dial is operated to send the proper code, which in the case assumed is 7. The wiper of the switch SW is advanced to its 110 seventh contact, which is connected over conductor 42 through the winding of the relay S₁₅ to battery. Upon this relay being selected, it is energized and connects the central office operator's set 14 to the trunk MT, 115 which in turn is normally connected to the trunk MT. At its lowermost front contact relay S₁₅ completes a circuit over the normal switchhook contact of the set 14, through the buzzer or call bell BZ, thereby notifying 120 the central office operator that he is wanted. After talking with the central office attendant, the studio attendant, by removing the plug from the jack, will automatically release the switches SW and SW' and release 125

the relay S_{15} , thereby disconnecting the central office subscriber's telephone from the monitoring circuit.

If the attendant at the central office wishes to communicate with the studio attendant, the key K_2 at the central office may be closed, thereby energizing the relay S_{15} and connecting the operator's set to the trunk MT, as already described. The attendant may then operate the ringing key K_3 to connect ringing current to the trunk. This actuates the drop 43 at the studio so that the studio attendant may plug his set into the jack J and answer the call. At the close of the conversation the central office operator will release the key K_2 and disconnect his set, the central office operator disconnecting his set by withdrawing the plug P from the jack J.

It will be obvious that the general principles herein disclosed may be embodied in many other organizations widely different from those illustrated without departing from the spirit of the invention as defined in the appended claims.

25 What is claimed is:

1. In a signaling system, a transmission circuit extending between two stations, means to impress signals upon said circuit at one of said stations, an auxiliary monitoring circuit 30 extending between said stations, an attendant's monitoring set at said first station, and means at said second station controllable by the attendant at said first station, to connect said monitoring circuit to the terminals of 35 said first mentioned circuit at said second station to enable the attendant to monitor the transmission of signals from said first to said second station.

2. In a signaling system, a transmission 40 circuit extending between two stations, means to apply signaling currents to said circuit at one station, amplifying equipment associated with said circuit at the other station, an auxiliary monitoring circuit extending between 45 said stations, an attendant's monitoring set associated with said monitoring circuit at said first station, and means at said second station controllable by the attendant at said first station to connect said auxiliary circuit 50 to the output side of said amplifying equipment at said second station to enable the attendant to monitor on the output of said amplifying equipment.

3. In a signaling system, a transmission 55 trunk extending from a transmitting station to a central office, branch trunks extending from said central office to outlying points, a monitoring trunk extending from said transmitting station, and means for selectively connecting said monitoring trunk to said main trunk at said central office or to any one of said branch trunks at said outlying points.

4. In a signaling system, a main transmission 60 trunk extending from a transmitting station to a central office, amplifying equipment

associated with said trunk at said central office, branch trunks extending from said central office to outlying points, amplifying equipment associated with each branch trunk at each outlying point, an auxiliary monitoring trunk extending from said transmitting station, and means for selectively connecting said auxiliary trunk to the output of said amplifying equipment at the central office or to the output of any amplifying equipment 75 at any of said outlying points.

5. In a signaling system, a main transmission trunk extending from a signaling station to a central office, amplifying equipment associated with said trunk at said central office, branch trunks extending from said central office to outlying points, amplifying equipment associated with each branch trunk at each outlying point, an auxiliary monitoring trunk extending from said signaling station, and means controllable by an attendant at said signaling station for selectively connecting said monitoring trunk to the output of any amplifying equipment 80 in the system.

6. In a signaling system, a main transmission trunk extending from a transmitting station to a central office, amplifying equipment at said central office, branch trunks extending from said central office to outlying points, amplifying equipment associated with each branch trunk at each outlying point, an auxiliary monitoring trunk extending from said transmitting station, and selective switching means controllable by an attendant at said transmitting station for selectively connecting said monitoring trunk to the output of any amplifying equipment 95 in the system.

7. In a signaling system, a main transmission trunk extending from a transmitting station to a central office, amplifying equipment associated with said trunk at the central office, branch trunks extending from said central office to outlying points, amplifying equipment associated with each branch trunk at each outlying point, an auxiliary monitoring trunk extending from said transmitting station, and means including an automatic directive switch controllable by an attendant 100 at said transmitting station for selectively connecting said monitoring trunk to the output of any amplifying equipment in the system.

8. In a signaling system, a main transmission trunk extending between two stations, means to apply signaling currents to said main transmission trunk at one of said stations, amplifying equipment associated with said trunk at the other station, an auxiliary monitoring trunk extending between said stations, means to connect said monitoring trunk to the output side of said amplifying equipment, and means responsive to the failure of said amplifying equipment to transmit 115 120 125 130

a signal to the other station over said monitoring trunk.

9. In a signaling system, a main transmission trunk extending between two stations, 5 means to apply signaling currents to said main transmission trunk at one of said stations, amplifying equipment associated with said trunk at the other station, an auxiliary monitoring trunk extending between said stations, 10 means to connect said monitoring trunk to the output side of said amplifying equipment, an indicator at said first station controllable over said monitoring trunk to indicate the operative condition of said amplifying equipment, and means to transmit a signal 15 over said monitoring trunk to indicate failure of said amplifying equipment.

10. In a signaling system, a main transmission circuit extending between two stations, 20 a receiving circuit connected thereto, a separate auxiliary monitoring circuit extending between said stations, means to connect said auxiliary circuit to said main transmission circuit at one of said stations without interrupting the connection to said receiving circuit to permit an attendant to monitor from the other station, and means to enable attendants at both stations to converse over said monitoring circuit.

30 11. In a signaling system, a main transmission circuit extending between two stations, means to impress signaling currents upon said circuit at one station, amplifying equipment associated with said circuit at the other station, a receiving circuit connected thereto, 35 an auxiliary monitoring circuit extending between said stations, means to connect said auxiliary monitoring circuit to the output side of the amplifying equipment at said second station without interrupting the connec-

tion to said receiving circuit to enable an attendant to monitor on the circuit from the first station, and means whereby attendants at both stations may converse with each other over said monitoring circuit.

45 12. In a signaling system, a main transmission trunk extending from a transmitting station to a central office, amplifying equipment associated with said trunk at said central office, branch trunks extending from said central office to outlying points, amplifying equipment associated with each branch trunk at each outlying point, means for adjusting the amplification of said amplifying equipment at said central office, an auxiliary monitoring trunk extending from said transmitting station, a directively controlled switch, 50 means for directively setting said switch at said transmitting station, and circuits controlled by said switch whereby in one setting it will connect said monitoring circuit to the output side of the amplifying equipment at said central office, whereby in other settings it will connect said monitoring circuit to the output side of the amplifying equipment associated with any one of said branch trunks at an outlying point, whereby in still other settings it will selectively control said means for adjusting the gain of the amplifying equipment at the central office, and whereby 55 in still another setting it will connect an attendant's telephone set at the central office to said monitoring trunk to enable the attendant at said transmitting station to converse with the attendant at the central office.

60 65 In testimony whereof I have signed my name to this specification this 29th day of July, 1924.

70 75 JOHN F. TOOMEY.
